RADIO CIRCUIT

Hans Marsiske, Furstenwalde/Spree, Germany

Application June 9, 1934, Serial No. 729,842
In Germany June 19, 1933

6 Claims. (Cl. 250—9)

My invention relates to radio circuits of the type employed in the art of radio communication, and more specifically to a circuit capable of dual operation, or in other words, capable of handling two signals simultaneously without interference between them.

It is an object of my invention to provide a system capable of functioning in the reception and transmission of more than one signal at the same time, without the one signal being interfered with by the other signal.

It is another object of my invention to provide a circuit for reception of a plurality of signals or programs simultaneously, and capable of reproducing the same on different indicating instruments.

An additional object of my invention is to provide a radio circuit involving electron discharge devices wherein the discharge devices perform double duty.

A still further object of my invention is to provide a radio system involving electron discharge devices wherein the discharge devices function both as radio frequency and audio frequency amplifiers simultaneously.

A still further object of my invention is to provide a radio circuit involving electron discharge devices wherein the electron discharge devices are capable of amplifying more than one program or signal simultaneously.

Additional objects of my invention will be brought to light in the following description of the same.

As an aid to an understanding of my invention, reference will be made to the accompanying drawing wherein I have disclosed one embodiment of my invention in its simplest form.

Broadly speaking, my invention embodies a radio circuit wherein a plurality of signals or programs may be received simultaneously without interference from each other, the discharge devices and circuits being so arranged that one of the signals will pass through the tubes in one sequence, whereas the other signal will pass through the tubes in another sequence. Perhaps a better understanding of the invention may be had by reference to the accompanying drawing and by tracing the path of one signal through one sequential arrangement of the discharge devices.

Referring to the drawing, therefore, for further explanation, I have disclosed my invention as embodied in a receiving circuit capable of receiving two programs simultaneously. The signal in the form of a modulated carrier wave

will be received on one of the antenna circuits which comprises the antenna 1 in series with a tuning condenser 3 and a resistor 5, the lower end of which is grounded to the filament 7 of an electric discharge device 9. The resistor 5 in the antenna circuit at radio frequencies is effectively connected between the grid 11 and the cathode 7 of the electron discharge device 9, the condenser 6 constituting a low resistance shunt across the primary of transformer 43, whereby the signal potential developed across the resistor 5 in the antenna circuit will be impressed upon the grid electrode 11. The amplified image of the signal potential will appear in the plate circuit of the discharge device 9, and will pass through a condenser 13 connected in series with a crystal detector 15, whereby it will be detected and broken up into its audio frequency and radio frequency components, the audio frequency component passing through the primary 11 of an audio transformer 19 through a plate supply battery 21 to ground. The radio frequency component is by-passed around the transformer primary 11 by means of a by-pass condenser 23 shunting the primary winding. Plate potential for the discharge device is derived from the battery 21 by way of the resistor 25 and a loud speaker 27 or other indicating device connected in series therewith, the loud speaker acting as a radio frequency choke in the circuit.

The audio frequency signal variations developed across the primary 11 of the audio frequency transformer 19 will induce corresponding variations in the secondary winding 29, which secondary winding constitutes the audio frequency input to the other electron discharge device 31 shown, thus impressing upon the grid 33 of this second discharge device, signal potentials which are to be amplified by the second discharge device acting as an audio frequency amplifier. The signals will, therefore, appear in amplified form in the audio frequency output of the device 31 which comprises a circuit including the series connection of the loud speaker 35, the resistor 37 and the plate supply battery 21 to ground. Passage of the audio signal energy through the detector circuit 41 etc. is prevented by the condenser 36 which imposes a high impedance to the flow of energy at the audio frequencies.

Thus, the signals corresponding to the modulations in the signal modulated carrier wave received upon the antenna circuit and impressed upon the input circuit of the first electron discharge device 9 acting as a radio frequency am-

plifier, are reproduced in the output circuit of the second electron discharge device 31 acting as an audio frequency amplifier.

Now it will be noted that if the received signal were impressed upon the resistor 39 in the input circuit of the second electron discharge device 31, a similar path may be traced in reverse sequence for the passage of the signal, this path including the condenser 36, crystal detector 41, transformer 43, loudspeaker 27, and resistor 25. The signal will therefore be reproduced on the first loudspeaker 27 or other indicating device, rather than on the second one 35, as before. The device 31 which functioned in the first instance as an audio frequency amplifier will now function as a radio frequency amplifier and the discharge device 9 which previously functioned as a radio frequency amplifier will now function as the audio frequency amplifier.

20 By tuning the antenna circuits by means of condensers 3 and 45, the operator can discriminate between the directions in which the signal is to flow. Thus by tuning one antenna circuit to one frequency, a program at that frequency 25 will be impressed upon the input circuit of the electron discharge device whose grid is connected to that antenna circuit, and the signal will travel or follow one predetermined sequence. Then should the other antenna circuit be tuned to a still 30 different frequency a program on that frequency will be impressed upon the grid of the other discharge device and its signal will follow a different sequence of travel. Therefore, two programs may be received simultaneously, and when so received, 35 each of the tubes will function as a radio frequency amplifier for one program and an audio frequency amplifier for the other program.

It will be apparent from the above description that my invention is capable of fulfilling the 40 objects provided. While I have disclosed the same in its simplest form, and as applied to a radio receiver, the invention is susceptible to many applications and modifications without departing from the spirit of the invention. Its use is 45 not limited to a receiving circuit as it is conceivable that the invention may be embodied in a transmitter for the simultaneous transmission of two signals each on a different carrier frequency.

Further, it should be apparent that in lieu of 50 the crystal detectors, detectors of the tube type may be employed, and my invention is not limited to any specific number of electron discharge devices, but may embody a plurality of amplifiers both for audio and radio frequency amplification.

55 It may be pointed out further that various types of circuits well known in the art may be utilized in lieu of the specific circuits disclosed by me.

I, therefore, do not desire to be limited to the specific details disclosed and described except as may be necessitated by the prior art and by the spirit of the appended claims.

I claim as my invention:

5 1. A radio circuit comprising a plurality of electron discharge devices, means for conveying a signal through said devices in one sequence wherein one of said discharge devices constitutes a radio frequency amplifier whereas another of 10 said devices constitutes an audio frequency amplifier, and means for simultaneously conveying another signal through said devices in a reverse sequence wherein said radio frequency amplifier amplifies signals at audio frequencies and said 15 audio frequency amplifier amplifies signals at radio frequencies.

2. In combination, a plurality of electron discharge devices, a receiving circuit interconnecting said devices to constitute one a radio frequency 20 amplifier and one an audio frequency amplifier, and another circuit electrically symmetrical to said first circuit, said last circuit interconnecting said devices to constitute said radio frequency amplifier an audio frequency amplifier, and said 25 audio frequency amplifier a radio frequency amplifier.

3. A radio circuit comprising a plurality of electron discharge devices, an antenna connected to the input circuit of one of said discharge devices, 30 another antenna connected to the input circuit of another of said discharge devices, means for conveying a signal from one of said antennae through said devices in one sequence and means for conveying another signal from the other of said 35 antennae through said devices in another sequence.

4. In a circuit of the radio type, a plurality of electron discharge devices each arranged to perform a different function in sequence and means 40 enabling a reverse order of said devices to simultaneously perform a similar sequence of functions.

5. In a circuit of the radio type, a plurality of electron discharge devices each arranged to perform a different function in sequence and means 45 enabling a different order of said devices to simultaneously perform a similar sequence of functions.

6. In combination, a plurality of electron discharge devices, a circuit interconnecting said devices to constitute one a radio frequency amplifier and one an audio frequency amplifier, and another circuit electrically symmetrical to said first circuit, said last circuit interconnecting said devices to constitute said radio frequency amplifier an audio frequency amplifier, and said audio 50 frequency amplifier a radio frequency amplifier.

55 HANS MARSISKE.
